SHOE CLEANING DEVICE

John W. Elliott, Brockton, Mass., assignor to The Elliott Corporation, Brockton, Mass., a corporation of Massachusetts

Application May 29, 1939, Serial No. 276,285

3 Claims. (Cl. 15—209)

This invention relates to devices for cleaning and restoring the original color to shoes or other articles made up of shoe materials.

In applying cleaning agents and covering substances to shoes accidental contact and transfer of such materials to the hands, clothing and nearby objects often occurs and is highly objectionable from the point of view of leaving unsightly stains and unpleasant odors. A particular instance is in connection with treating white shoes with whitening materials which may be of a light powdery character very readily rubbed off and which quickly dries on the hands and collects around the fingernails in an unsightly manner necessitating washing and manicures. The condition with respect to the hands is accentuated in those instances where it is desired to apply the covering agent in selected areas only in a shoe, as for example in the white areas of a brown and white shoe or in other combination. In such instances, it is desirable to neatly apply the covering agent, without allowing it to become smeared over the dark portion of the shoe. Usually a pad of some kind is applied with the ends of the fingers, a procedure which not only further soils the hands and nails, but fails to effect application of material along clear cut lines and to reach into somewhat inaccessible points as around the edges of shoe soles.

It is the chief object of this invention to devise an appliance with which such cleaning and color restoring operations as those above described can be performed quickly, neatly, and without smearing the fingers. The invention involves not only a novel product but also a novel method of manufacture and a unique package.

The nature of the invention will be readily understood from the following description when read in connection with the accompanying drawings and the novel features will be particularly pointed out in the appended claims.

In the drawings:

Figure 1 is a plan view illustrating a method of making pads and indicating a plurality of pads in a partly finished state;

Fig. 2 is a perspective view illustrating further steps in the method of making pads referred to in Fig. 1, and showing the pads in a finished pack form;

Fig. 3 is a view in front elevation illustrating a container with upturned cover, having received therein packs of pads similar to the pack illustrated in Fig. 2;

Fig. 4 is a view in end elevation of the container and pack assembly of Fig. 3 with the cover portion of the container occurring in a closed position;

Fig. 5 is a perspective view illustrating a typical method of using the pad on a shoe;

Fig. 6 is a view in front elevation illustrating a modified form of pad; and

Fig. 7 is a view in end elevation of the modified pad of Fig. 6.

An individual applicator made in accordance with this invention as shown, for example, in Fig. 5, comprises a pad and a holder therefor, a portion of said holder being adapted to serve as a guard or protector for the fingers while the device is being used. Preferably these devices are manufactured in a group, series, or gang, and they are so associated with each other that the entire gang can be handled as a unit for manufacturing and merchandising purposes, but any individual applicator can be readily separated from the others when it is desired to use it.

According to the preferred method of making the applicator, a blank of cardboard 1 is made use of and sized to comprise some predetermined number of pads, as for instance five as shown in Fig. 1. In place of the cardboard 1 may, if desired, employ other substantially stiff materials as synthetic compositions, wood, metal and the like.

The sheet 1 is next printed, and either at the same time or subsequently, it is cut or stamped out to present scalloped edges 2 and lines of scoring 3 suitably spaced along one margin of the blank. This produces a series of partly formed strips, lightly secured together at one side by means of the uncut portions 4.

In Fig. 1 I have also illustrated at the left-hand side thereof a further step of securing a material to the unscored margin of the blank for comprising pads, and as an example of one material used in this connection I may employ flannel. Other suitable fabrics or compositions may, however, be resorted to for this purpose. Preferably I employ two strips of flannel 5 and 6 placed one on the other which have been treated beforehand with a white cleaning and coating preparation. As illustrative of one suitable example, the following formula may be cited:

45 6 gals. water, 19 lbs. Titanox (a pure titanium dioxide)

11 oz. soap, 4 oz. Terpineol (higher alcohol used as a diluent and agent for promoting desirable odor)

50 11 oz. casein, 2 oz. bentonite (clay)

(The soap is dissolved in boiling water, the casein added, then the bentonite. Lastly the titanox is added and well stirred in.)

55 Other types and colors of preparations may be desired to be used in a similarly impregnated manner or at the time of application of the pad.

The strips are longitudinally folded to overlie each side of the uncut margin of the blank 1 and secured to the blank by stitching 6a, or other

60

suitable means as staples, adhesives and the like. The sheet is then cut transversely of the folded flannel strips and at points opposite the lines of scoring 3 to provide individual pads 8 and holder elements 9, lightly secured together by the uncut portions 4.

A final step in the method consists in bending the cardboard strips upon themselves along the narrowed portions 7 of the blank 1 to present a pack as illustrated in Fig. 2. It will be observed that, due to the scalloped edges 2, the strips fold upon themselves in a coincident manner whereby there are provided protective tabs 10 adapted to extend substantially over the pads 8 and cover same, the tabs being in a hinged state so that the protecting action may be effected at either side of the pad 8 and the lower end of the tab acting as a part of the handle for the pad in either case.

In using the pad according to the formula noted above, one side first is dampened with water and then is applied to a shoe 11 as shown in Fig. 5. It will be observed that the device is held between the thumb and the finger 12, the latter being pressed against the protective tab 10. It is intended that sufficient treating material may be retained in the pad 8 for one side of the pad to treat one shoe. Thereafter the tab is reversely folded and the opposite side of the pad moistened and applied as before.

It should be noted that the pad 8 is formed with a flat shape and presents relatively thin wiping edges 8a and square cut ends 8b particularly suitable for effecting cleancut application of materials such as a white dressing for a shoe when used with a combination shoe upper, and when applying the material around the edge of the shoe sole. The square cut ends 8b tend to facilitate a neat application of material around curved areas or edges of the dark leather portions of the shoe upper and thereby avoid smudging of the white material over upon the dark leather in an unsightly manner.

If desired, a pad member may be provided without being impregnated by a treating material, and such a pad may then be used in conjunction with materials received in a separate container to be picked up at the time of use. It is also intended that other methods of making applicators may be employed for providing the pads in either an individual or pack form. I may further provide a single pad or a group of pads treated with other shoe polishing preparations in any desired color.

The applicator itself may also be of modified construction and in Figs. 6 and 7 I have illustrated an applicator comprising a pad 13 secured about folded layers 14 and 15 of a holder element which may be composed of the cardboard above referred to or other material. In this modification the handle portions of the two folds of material have been cut out to form tabs 16 and 17 hinged at upper sides thereof, as for example tab 16 is hinged at its upper side 18 as shown in Fig. 6. In use, one tab may be bent

upwards as into the broken line position illustrated in Fig. 7, while the other tab, as for example 16, is maintained flatly against its corresponding handle portion, or these positions may be reversed.

For convenience the pads in the pack form illustrated in Fig. 2, are preferably received in an envelope container. In Fig. 3 of the drawings I have illustrated a container 19 comprising a unitary member having one edge reversely folded and secured by clips 20 to present an envelope 21 in which may be conveniently received the handle ends of a pack 26 of pads such as has been illustrated in Fig. 2. I may desire to assemble more than one pack unit in the envelope, and preferably two packs 26 and 27 of pads will be inserted therein as may be more clearly seen in Fig. 4. The container at its top is formed with two lines of bending 22 and 23 which may be spaced apart any desired amount to provide a widened top portion 24 when the remaining portion of the envelope has been folded over to comprise a flap 25. This construction results in a simple, efficient container from which separate pads may be quickly detached as desired.

It will be seen that my improved applicator comprises a simple, cheap and efficient member for carrying out cleaning, color restoring, and polishing operations, and that these operations 30 can be performed quickly, neatly, and without smearing the fingers.

While I have herein shown and described a preferred embodiment of my invention, it will be understood that the invention may be embodied in other forms without departing from the spirit or scope of the invention as defined by the appended claims.

What I claim as new is:

1. An applicator for treating shoes comprising 40 a supporting strip, a pad folded about one extremity of said strip and being impregnated with a coating material, and a tab portion hinged at the opposite end of said supporting strip adapted to lie over said pad and to cover a substantial portion of same at either side thereof.

2. An applicator of the character described comprising a strip of material folded upon itself, a pad secured about the extremities of the said strip of material, and a tab portion cut out from the folded strip and adapted to be upturned against said pad at either side thereof to present a protecting member.

3. An applicator for applying a coating material to shoes comprising a pad impregnated with said material and adapted to be used while wet, a supporting holder, said pad being folded over the end of said supporting holder and secured to the opposite sides thereof, and a protector member forming a part of said holder but foldable with respect thereto, said protector member being adapted to be held by the finger against one side of the pad while the other side of the pad is in use.

JOHN W. ELLIOTT.
